US00D801827S

(12) **United States Design Patent** (10) **Patent No.:** **US D801,827 S**
Gelov et al. (45) **Date of Patent:** **** Nov. 7, 2017**

(54) **CONTAINER**

- (71) Applicant: **TC Heartland LLC**, Carmel, IN (US)
- (72) Inventors: **Teodor Gelov**, Carmel, IN (US); **Karen H. Nichols**, Carmel, IN (US); **Douglas E. Norton**, Carmel, IN (US)
- (73) Assignee: **TC Heartland LLC**, Carmel, IN (US)
- (**) Term: **14 Years**
- (21) Appl. No.: **29/523,460**
- (22) Filed: **Apr. 9, 2015**
